AUTOMATIC HOG OILING AND FEEDING
ASSEMBLY

Irwin H. Palmer, Aberdeen, S. Dak.

Application January 22, 1943, Serial No. 473,228

4 Claims. (Cl. 119—54)

The invention relates to automatic hog oilers and feeders and has for its objects to provide certain new and improved advantages in devices of this character.

An important object of the invention is to provide an improved hog oiler device which when operated by the animal will in turn actuate improved mechanically connected feed agitating elements associated with a feed bin or hopper with the result that the feed is uniformly and gradually discharged preferably into a plurality of feed troughs on opposite sides of the hopper.

A further object is to provide a device of the character described wherein provision is made for protecting the feed bin, feed troughs and the hogs from abnormal or inclement weather conditions, and from entrance of moisture to the bin.

A still further object is to provide a combined hog oiler and feeder wherein provision is made for more effectually replenishing the feed in the bin or hopper by means of a hinged door disposed in the roof of the substantially enclosed structure, means being provided for locking the door in either open, closed or intermediate positions.

A still further object is to provide a more efficient automatic hog oiling device designed for continuous operation when energized by the hog and which is capable of convenient replenishment when necessary.

A still further object is to provide an improved mechanism for actuating the feeding devices through the oiler with a minimum of effort and friction on the part of the animals and wherein a maximum amount of feeding accommodation at the troughs is obtained by means of a minimum number of oiling devices.

A still further object is to provide an automatic hog oiling and feeding assembly of compact and economical construction and wherein all portions of the device are spaced above the ground surface, thereby insuring against access of rain or moisture to any portion of the device.

A further object is to provide in the device independent and complementary oiling and feeding means operable selectively or simultaneously by the animals, thereby increasing the probability of and insuring the presence of an adequate amount of feed material in the feeding troughs at all times.

Numerous other objects and advantages of the invention will be apparent as it is better understood from the following description, which taken in connection with the accompanying drawings, discloses a preferred embodiment thereof.

In said drawings:

Fig. 1 is a longitudinal vertical sectional view of my improved hog oiling and feeding assembly.

Fig. 2 is a vertical transverse section through the assembly on line 2—2 of Fig. 1.

Fig. 3 is an enlarged view in side elevation partially in vertical section of my improved hog oiler device or wheel per se.

Fig. 4 is a vertical sectional view on line 4—4 of Fig. 3.

Fig. 5 is a side view of the device or assembly showing the feed replenishing door in elevated or open position.

Fig. 6 is an end view of the assembly illustrating the substantially closed housing for protecting the feeding devices from the elements.

Fig. 7 is a detail view illustrating a portion of the door actuating and locking mechanism.

Fig. 8 is a detail view partially in vertical section and taken substantially on line 8—8 of Fig. 7, and

Fig. 9 is a detail view partially in section, of one of the feed agitating shafts and elements.

Referring to the drawings, the housing assembly includes a substantially closed and protected building structure preferably comprising opposite end walls 10, an intermediate connecting roof 11, a floor 12 having spaced uprights

30 or supports 13 therebetween and oppositely disposed longitudinally extending roof supporting beams or frame members 13a suitably secured to and carried by the supports 13. Longitudinally spaced oppositely inclined rafters 13b extend from the roof supporting beams 13a to the ridge 13c for carrying the oppositely inclined closed roof 11 which may be of any preferred waterproof construction. One or more longitudinally extending truss rods 13d (Figs. 2 and 5) may be

40 incorporated in the structure for the purpose of additionally carrying the weight of the roof and preventing the same from sagging. The floor 12 is in turn supported and spaced above the ground level by means of a suitable number of horizontally disposed spaced ground engaging frame members or runners 14. This is intended to exclude rain and moisture and to render the entire assembly of a portable nature and movable from one locality to another on the said runners 14,

45 which may be replaced by wheels, if desired. As illustrated it is quite desirable to construct the end walls 10 and floor 12 of double boarding so as to more effectually insure against access of moisture, rain or dampness to the building. This

is very desirable to maintain the feed in a perfectly dry condition.

A longitudinally extending centrally disposed feed bin or hopper is indicated at 15 and is enclosed preferably by upwardly and outwardly inclined side walls 16, 16a, extending the full length of the described building structure and otherwise suitably reenforced by upwardly and outwardly inclined frame elements 16b (Fig. 2). The lower ends of the said wall elements 16 terminate or are spaced above the floor 12 so as to provide feed discharge apertures or openings 17 communicating with oppositely disposed longitudinally extending feed troughs 18 on each side of the feed bin at the lower end thereof, said troughs in turn supported by the intermediate portion of the floor 12 which is of double boarding or thickness. As best seen in Fig. 2 the outer wall 19 of each longitudinally extending feed trough 18 is extended inwardly as at 20 so as to overhang the trough to prevent the animals from rooting the feed transversely out of the trough. Spaced inclined rods 21 and 21a extending between each trough and the feed bin are disposed along the troughs so as to prevent the hogs from rooting the feed longitudinally thereof. Preferably the space between each pair of substantially vertically aligned rods 21 and 21a, longitudinally of each trough, is sufficient to accommodate one hog for feeding purposes. The opposite ends of the said rods 21, 21a are preferably removably secured to the troughs and bin walls 16 respectively to the end that their longitudinal spacing in the troughs may be variable to accommodate the hogs during their progressive development in size. Stated otherwise, the spacing of the rods longitudinally of the troughs would be less when the hogs are small than after they have reached maturity.

Disposed substantially centrally of the feed bin 15 and extending from end to end thereof adjacent the lower portion of the bin, are a pair of axially and longitudinally aligned agitator shafts 22, 22a. Each shaft is suitably supported upon spaced standards or uprights 23, 23a, extending upwardly from the floor of the housing and provided at their upper ends with bearings 24, 24a in which the separate aligned shafts 22, 22a are respectively journaled for rotation. Additional bearings 24b, 24c may also be provided at the locality where the respective shafts project outwardly through the end walls 16 of the building structure. Each shaft carries at suitably spaced intervals therealong a plurality of radially projecting feed agitator arms 25, removably and adjustably secured to the shaft as best seen in Fig. 9. These arms are fixed to the shafts and preferably extend outwardly in staggered relation to one another so that each arm will have a different position in the bin radially of the shafts.

The floor of the feed bin or hopper 15, a comparatively short distance below the described agitator arms, is inclined downwardly and outwardly on each side of the shaft as indicated at 26 so as to constitute an oppositely inclined apron for more effectively directing the feed toward the discharge apertures 17 leading to the feed troughs 18.

Each feed agitator shaft for dispersing the feed F in the bin or hopper 15, has fixedly secured at its outer end a rotatable hog oiler wheel 27, each preferably of identical construction. In the embodiment illustrated the said oiler wheels each

include a hub 28 (Figs. 3 and 4) secured to a said shaft, a circular rim 29 and a plurality of radiating spokes 30 for supporting the rim. The rim or annulus 29 in turn carries an annular pipe 31 suitably perforated at intervals around its periphery as at 32, and encased within a burlap or other fabric covering 33. The circular pipe 31 serves as a reservoir for the medicinal oil and continuously saturates and supplies the burlap casing as required by seepage through the pipe perforations 32. The oil in the pipe may be replenished as desired as by means of a funnel 34 (Fig. 3) for directing the oil through one of the perforations 32 or through a larger normally closed aperture in the said pipe. The invention contemplates if desired the use of the described vertically disposed oiler wheels 27 without the perforated pipe 31 in which event the oil would be contained in a suitable reservoir or permeable sacking disposed around the periphery of the rim 29.

The proportions of the assembly are such that the oiler wheels 27 are disposed the proper or desired distance above the ground level so as to be conveniently reached by the hogs when the latter desire to avail themselves of the oiling medicament. In so doing either of the said oiler wheels will be rotated or oscillated in opposite directions according to the tendency of the hog in rubbing against the wheel. Under either condition the shaft 22 or 22a, or both, upon which the moving wheels are respectively mounted, will be oscillated or rotated so as to move their attached agitator arms sufficiently to stir up and disperse the dry feed in the hopper 15 to a sufficient extent to replenish by gravity any appreciable depletion in the feed troughs 18. Agitation of the feed shafts by the oiler wheels under the urge of the rubbing action of the animals tends to maintain and gravitate the feed at or toward the lower portion of the bin and in contact with the inclined apron floor 26. This is to the desired end that the feed will fall laterally outwardly through the apertures 17 into the troughs in accordance with the rate of consumption of the feed by the animals.

Due to the comparatively large feed capacity of the bin, for example 150 bushels, it will be noted that the provision of separate longitudinally aligned shafts 22, 22a each having an oiler wheel 27 at its outer end, prevents undue effort being necessary on the part of the hog to rotate or oscillate a said wheel sufficiently to discharge food into the troughs at either end of the building structure. Obviously both wheels might be actuated simultaneously by the hogs, in which event feed would be distributed into each trough for the entire longitudinal extent of the building structure.

Provision is made for replenishing the feed bin 15 with a minimum of effort. To this end the overhanging roof 11 on one side of the building is provided with a door 35 extending the full length of the building and suitably hingedly secured at its inner end to the ridge element or portion 13c. The flexible strip 35a (Fig. 2) may be provided to effectively seal and prevent the entrance of moisture to the joint between the door and roof 11. When the door is in raised or elevated position as illustrated in dotted lines in Fig. 2, fresh dry feed or grain may be shoveled as from a wagon into the upper end of the bin 15. To facilitate such replenishment an inwardly and downwardly inclined baffle board or apron 36 is disposed longitudinally of the build-

ing between the roof 11 adjacent the outer end of the door and the upper end of the inclined side wall 16a of the feed bin.

Manually actuated mechanical means are provided for raising and lowering the door as well as for locking the same in its closed, open or intermediate position. At one end of the building a shaft 37 projects outwardly through a suitable bearing therefor and carries at its outer end an operating handle 38 (see also Fig. 7). This shaft extends the full length of the building and is suitably journaled therealong and in the opposite end wall thereof. Inwardly of said handle and on the inner side of the building wall the shaft carries at spaced intervals therealong a plurality of fixedly secured depending arms 39 (Fig. 2) each having pivotally secured to its outer end an upwardly extending link 40. The outer ends of these links are suitably journaled as at 41 in a plurality of bearings or brackets provided at spaced intervals along the longitudinal extent of the door and adjacent the outer edge thereof. Thus it will be seen that when the manual lever or handle 38 is rocked in the proper direction (to the right as illustrated in Fig. 2), the levers 39 will be elevated to their dotted line position with the result that the door 35 is elevated to the dotted line position illustrated in said figure. In order to securely hold the door against displacement in its open, closed or intermediate positions, the shaft carries adjacent the handle 38 and preferably exteriorly of the building, a ratchet wheel 42 having spaced peripheral teeth 43. A horizontally disposed locking detent member or bar 44 is slidably mounted within a pair of spaced bracket members 45 secured to the outer end wall 10 of the building. A spring pressed rod or bolt 47 extends vertically through the slot 44a of one of the bearing brackets 45, said bolt including a washer 48 beneath its head. A spring 49 has its lower end located in an opening 50 in the bearing 45 and bears against the upper face of the detent 44, the other end bearing against the washer 48. By adjusting the nut 51 on bolt 47 the desired amount of pressure is obtained so that the spring 49 will hold the detent 44 in any position to which it is moved by the manual handle 46. The inner end of the slideable detent 44 is designed to engage between the teeth 43 of the gear wheel 42 so as to hold the door in any position to which it may be moved by rotation of such gear by the manual handle 38. Such a construction prevents the door from being blown open or closed by high winds or otherwise disturbed from its displaced or adjusted position, such as when replenishing the feed in the bin 15.

As best seen in Fig. 1 a separate bin or hopper 52 is provided at one end of the building and is separated from the main bin 15 by means of a partition wall 53. This separate or auxiliary bin may be employed for a special mineral or tankage food which is essential for quick growth of hogs but need not be consumed in such large quantities as the major portion of the food. Therefore only a small portion of the bin need be devoted to holding and disbursing this special mineral food.

By the described invention I have provided a valuable time saving device by means of which a hog raiser can save several hours per week. All that is necessary is to put a load of feed in the bin 15 after which the owner may ignore the matter of feeding and oiling until the bin is again empty. My device saves from one to three hours

per day per hog raiser from the ordinary method of feeding hogs by hand. The separate compartment 52 employed for feeding the commercial hog balancers which contain minerals and medicaments is also a great time saver. In view of the shortage of farm labor this is an exceedingly important aspect of the invention.

The device further saves feed in important economical respects and is so constructed that when the feed is placed in the bin 15 it is protected from moisture in just the same manner as when stored in the granary. The device is so constructed that certain live stock, such as horses and cattle cannot get to the feed and waste it nor can the assembly be tipped over as in the instance of many ordinary feeders, thereby entailing loss and waste of grain. The improved troughs 18 are so arranged and constructed that the hogs themselves cannot waste any appreciable amount of feed. The feed cannot either be rooted longitudinally or transversely of the troughs nor can the hogs get their bodies in the troughs and foul the feed. The troughs are so placed upon the flooring that what little grain is spilled may be readily picked up by the animals. The expensive tankage feed in the separate similar compartment or bin 52 is also conserved in this manner. The transverse dimensions of the flooring are such that a hog standing before the trough is so positioned that excrement drops upon the ground and thereby is prevented from reaching and fouling the floor of the building or any grain which may be present thereon.

The entire structure is designed to be portable so that it can be moved into an alfalfa field during the summer and close to the grain and grain bins in the winter, thereby constituting an important convenience and time saving device.

The combined agitator and hog oiling wheels 40 are obviously important time saving devices and the entire assembly is so constructed that once the bin 15 is filled with feed and the oil receptacles on the wheels 27 filled, the hogs require no attention whatever for a number of days at a time. By means of the invention the hog raiser may care for and fully develop several times the number of hogs that he could otherwise raise and with a minimum of personal effort and time, so that most of his attention may be devoted to his regular farm duties.

The rugged nature and construction of the entire device is such that it may be readily transported from place to place and will not be damaged by such moving or by backing into the building a truck when filling and replenishing the feed bin. The described construction is further such that adequate shelter from snow and storms is provided while the hogs are feeding, the feed is protected from bad weather partially by the double board construction, low eaves on the roof, closed ends of the hogs' stalls preventing cross drafts, as well as the blowing in of rain and snow. This is also prevented by the full length door on the roof having a flexible sealing or flap element 35a. The lower portion of the building is protected by the spacing of the floor 12 above the ground level by means of the beam supports or runners 14.

It is thought that the invention and many of its attendant advantages will be understood from the foregoing description, and it will be apparent that various changes may be made in the form, construction and arrangement of the parts without departing from the spirit and scope of the invention or sacrificing all of its material advan-

tages, the form hereinbefore described being merely a preferred embodiment thereof.

What is claimed is:

1. A portable combined automatic hog oiling and feeding assembly comprising a rectangular building structure open at two sides thereof and including a roof and elevated flooring supported on runners, a substantially closed feed bin extending longitudinally and intermediately of said structure between said roof and flooring, feed troughs supported by said flooring on opposite sides of said bin and extending longitudinally of the latter at its lower end, discharge apertures in the lower end of said bin and communicating with said troughs, a pair of axially aligned agitator shafts extending longitudinally through said bin and respectively projecting through the opposite end walls of the building structure, a plurality of agitating arms projecting radially from said shafts, perforated oiling wheels rotatably mounted on the outer ends of said shafts respectively exteriorly of the building, whereby actuation of said oiling wheels rotates said shafts and their associated agitating means to loosen the feed in said bin and discharge the same by gravity into said feed troughs, and a door hingedly mounted in said roof and communicating with the upper end of said bin for replenishing the feed therein, said door having manually controlled means for opening and closing the same and for locking the door against displacement from any of its adjusted positions.

2. A hog feeding device comprising a rectangular building structure open at two sides thereof and including a roof, flooring and opposite end walls, a door hingedly mounted in and constituting a part of said roof, a substantially closed feed bin extending longitudinally and intermediately of said structure between said roof and flooring, feed troughs supported by said flooring on opposite sides of said bin and extending longitudinally of and communicating with the latter, said feed bin and troughs being spaced materially laterally inwardly on said flooring from the opposite open sides of the building structure to necessitate a feeding hog to stand in a shel-

tered position on said flooring, manually operable means disposed exteriorly of an end wall of the building structure for elevating said door to open position for replenishing the feed in said bin, said means including a shaft having a handle thereon, a lever fixed on said shaft and a link connecting the outer end of said lever to said door, and a manually operable sliding detent engageable with said shaft for locking the same against movement to hold the door in adjusted position relative to said roof.

3. An automatic hog oiler comprising a horizontal shaft, a rotatable vertically disposed wheel mounted on said shaft, a rigid annular hollow perforated housing constituting the rim of said wheel and serving as an oil reservoir, and a fabric covering on said housing for receiving oil seepage through said perforations to the point of saturation, whereby rotation of said wheel by contact with the hog uniformly applies the oil to the skin of the animal.

4. A portable combined automatic hog oiling and feeding assembly comprising a rectangular building structure open at two sides thereof and including a roof and elevated flooring, a substantially closed feed bin extending longitudinally and intermediately of said structure between said roof and flooring, feed troughs supported by said flooring on opposite sides of said bin and extending longitudinally of the latter at its lower end, discharge apertures in the lower end of said bin and communicating with said troughs, a pair of axially aligned agitator shafts extending longitudinally through said bin and respectively projecting through the opposite end walls of the building structure, a plurality of agitating arms projecting radially from said shafts, and perforated annular oiling wheels rotatably mounted on the outer ends of said shafts respectively exteriorly of the building structure, whereby actuation of said oiling wheels independently rotates said shafts and their associated agitating means to loosen the feed in said bin and discharge the same by gravity into said feed troughs.

IRWIN H. PALMER.
